UNITED STATES PATENT OFFICE.

GEORGE MEYER, OF NEW YORK, N. Y.

DESIGN FOR AN INTERIOR SECURING-BAND FOR RUBBER TIRES.

SPECIFICATION forming part of Design No. 32,037, dated December 26, 1899.

Application filed October 10, 1899. Serial No. 733,220. Term of patent 14 years.

To all whom it may concern:

Be it known that I, GEORGE MEYER, a citizen of the United States, residing at New York, in the county of New York and State of New York, have invented and produced a new and original Design for an Interior Securing-Band for Rubber Tires, of which the following is a specification, reference being had to the accompanying drawings, forming part thereof, and in which—

Figure 1 is a side elevation of an interior securing-band for rubber tires bearing and incorporating my design. Fig. 2 is an enlarged transverse section of same on dotted line 2 2 15 of Fig. 1, and Fig. 3 is an enlarged view of the inner side of same.

The leading feature of my design consists in the form and configuration of the securing-band, substantially as shown in the drawings.

In the drawings, A designates the securing-

band as a whole, B the web portion thereof, and C the annular flanges extending along the edges of and merging into the web portion B, said flanges being of the outline illustrated, and the whole being substantially as shown in the drawings. The flanges C turn inward and have full rounded outer surfaces, and at their facing sides they merge on curved lines into the web portion B. The flanges C have the special outline or form shown. 30

What I claim is—

The design for an interior securing-band for rubber tires, substantially as shown and described.

Signed at New York, in the county and State of New York, this 28th day of September, 1899.

GEORGE MEYER.
